UNITED STATES PATENT OFFICE

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA

CAN DRAINER

Original application filed January 2, 1930, Serial No. 418,009. Divided and this application filed November 22, 1930. Serial No. 497,557.

This is a division of my pending application, Serial No. 418,009, filed January 2nd, 1930, for can feeders and timers.

The invention herein relates, generally, to machines used in the canning art, known as can-drainers. It particularly relates to that type of such machines disclosed in my pending application Serial No. 319,283, filed Nov. 14th, 1928, in which a traveling member following the inverting and reverting sinuosity of a can-path, carries at intervals drain-covers timed for association with the entering cans and separated by spaces of sufficient length to permit them to freely follow without interference the tortuous course of the sinuous can-path.

In a machine of this type, especially when adapted for draining fish-filled cans which are usually of shape and size requiring the use of drain-covers so fashioned as to necessitate an appreciable interval of their separation in order to permit them to freely follow the sinuosity of the can path, the matter of feeding the cans to said path, both as to control and timing becomes of vital moment, since the cans which initially reach the feeding members in close line formation must be appreciably spaced from each other and positively controlled during their advance by and through the feeder, in order to enter the drainer can-path in timely relation to the appreciably spaced drain-covers.

Thus, the object herein is to provide such an improved can-drainer; and to this end my invention may briefly be stated to consist in a can-drainer having a sinuous can-inverting and reverting track extending throughout the machine; a traveling member following the sinuosity of said track throughout the length thereof; a plurality or series of spaced drain-covers carried by said members adapted to cover, hold, propel and release the cans upon said track; means for advancing a file of cans to and upon said track; and means for increasingly changing, under positive control, the spaced relation of the cans in the feeding file while upon said advancing means, adapting them for timely association with the drain covers.

In the accompanying drawings I have

shown my can-drainer in its preferred form, though it must be understood that changes may be made without departing from the spirit of the invention as defined in the claims hereunto appended.

In the drawings, Fig. 1 is a side elevation of my can-drainer.

Fig. 2 is a section on the line 2—2 of Fig. 1.

Fig. 3 is a view of the screw for increasing spacing the cans of the entering file.

Fig. 4 is a section on the line 4—4 of Fig. 1.

In Fig. 3, the timing member 1 is a screw, the thread 2 of which has an increasing lead 65 and an increasing thickness, preferably rim-hollowed or doubled, to save metal, as shown at 3.

In Figs. 1 and 2 is disclosed the improved can-drainer.

A frame 4 has within it a vertically tortuous or sinuous can-track 5 adapted for the inversion and reversion of the cans according to the usual function of such machines, and it has also an endless traveling member 6 75 which carries at proper intervals, drain-covers 7 adapted to descend upon the open tops of the entered cans, and to maintain such association during the inversion and reversion of said cans, and then to separate from 80 them as they are again uprighted.

Each drain-cover 7 has a projecting arm 8, which by impinging upon the back of the can, propels said can along the track 5.

Leading out from the upper portion of the frame 4 is a can-track 9, which practically is an extension of the drain can-track 5, and which by its upturned side as seen in Fig. 2 forms a guide for the cans. Associated with this track is a traveling member 10, the two forming a can-feeder to the drainer, the cans resting upon the track 9 and member 10, and by friction with the latter advanced into the machine. Under and to one side of the upper run of the feeder member 10 lies the timer screw 1, the thread 2 of which is in position to engage from below a rear corner of the cans 17, said thread extending through a cut-out section of the track 9, and pressing the cans against the 100

turned up side of the track for complete and continuous control during the advance of the can file.

Suitable power mechanism is provided to 5 drive the moving members. For example, the endless drain-cover carrier 6 is mounted upon sprockets 11. This carrier is driven by a shaft 12, which in turn is driven by gears 13, Figs. 1 and 4, from a main power shaft 14. The timer screw 1 is driven by a gear 15 from the gears 13, and the feed member 10 is driven by bevel gears 16 and a sprocket 16', Fig. 1, from the power shaft 14.

The cans, indicated at 17, previously 15 washed and filled with the comestible, but as yet uncapped, are supplied upright to the feeder member 10. Whatever may be the means, not necessary to show herein, for so supplying them, it must be noted that they 20 reach and are delivered to said member in a close file in which they touch each other. Obviously, if they continued in such close file, they could not meet their respective drain-covers 7 with timely precision, both 25 because of the necessarily wide spacing of the covers and because of the absence of any accurate or positive control of the file as led in by the feeder member. In my present device, both timing accuracy and the control 30 of each individual of the procession or file are provided for. Each can as it passes over the outer end of the screw 1 is separately engaged by the screw thread 2 and, due to the increasing lead of said thread as the file 35 advances and is opened, is spaced from its neighbors; and also, due to the increasing thickness of said thread each can is still confined and controlled with fitting closeness between the thread coils and the opposing 40 upturned side of the track 9; so that, with due predetermined regard to the pitch of the screw thread relatively to the spacing of the drain-covers, and with respect to the relative speed of rotation of the screw and 45 the travel of the feeder member and that of the drain-cover carrier, the cans are individually controlled and led to their timely association with said drain-covers. It will thus be seen that the members 9, 10 and 1 50 comprise the complete assembly for advancing, controlling, and widening the spacial relation of the cans as they are advanced to the machine; and furthermore because of the immediate proximity of the delivery end 55 of the feed assembly, the cans are passed to the machine track 5 directly and without any other transfer.

The underlying position of the timing screw which enables it to engage the bottom 60 edge of the can is to be preferred to an engagement with its upper edge as being less possibly destructive to a weaker end of the can, and less likely to cause jamming. The upper edge of a can of the universally used 65 sanitary type presents an outwardly turned

flange having a thin raw edge, easily bent or damaged and likely to cause considerable friction against the rubbing surface of the screw thread, whereas the bottom edge of such a can, being a finished seam, presents a 70 smooth round surface.

The contact between the feed member 10 and the can being frictional only, it is preferable, though not essential, to cause said member to travel at a speed somewhat greater than the normal or average speed of advance of the cans. By so doing, the conveyor member has some tendency to accelerate and therefore separate the cans as they 75 come within its sphere of influence, thereby assisting the screw in its accelerating function and reducing the friction between its thread and the can. The timing function, however, is performed solely by the screw, because such function necessitates positive 80 engagement with the can.

I claim:—

1. A can-drainer comprising a sinuous can-inverting and reverting track; a moving series of spaced drain-covers following the 90 sinuosity of said track and adapted for fitting, propelling and releasing the respective members of a line of correspondingly spaced cans upon said track; means associated with the receiving end of said track for feeding 95 a line of cans thereto; and means for increasingly widening the spacial relation of the cans of said in-feeding line for timely association with said drain-covers.

2. A can-drainer comprising a sinuous can-inverting and reverting track; a moving series of spaced drain-covers following the sinuosity of said track and adapted for fitting, propelling and releasing the respective members of a line of correspondingly spaced cans upon said track; means associated with the receiving end of said track for feeding 100 a line of cans thereto; and means for increasingly widening the spacial relation of the cans of said in-feeding line for timely 105 association with said drain-covers and holding them under control throughout the in-feed.

3. A can-drainer comprising a sinuous can-inverting and reverting track; a moving series of spaced drain-covers following the sinuosity of said track and adapted for fitting, propelling, and releasing the respective members of a line of correspondingly spaced cans upon said track; means associated with the receiving end of said track for feeding 110 a line of cans thereto; and a screw, the thread of which has an increasing lead 115 engaging the cans of said in-feeding line to open the file for the timely association of its members with said drain-covers.

4. A can-drainer comprising a sinuous can-inverting and reverting track; a moving series of spaced drain-covers following the sinuosity of said track and adapted for fit- 120

ting, propelling and releasing the respective members of a line of correspondingly spaced cans upon said track; means associated with the receiving end of said track for feeding a line of cans thereto; a screw, the thread of which has an increasing lead engaging the cans of said in-feeding line to open the file for the timely association of its members with said drain-covers; and a fixed guide adapted in conjunction with said screw to control the cans of said in-feeding line.

5 5. A can-drainer comprising a sinuous can-inverting and reverting track; a traveling member following the sinuosity of said track; a series of spaced drain-covers carried by said traveling member adapted for fitting, propelling and releasing the respective members of a line of correspondingly spaced cans upon said track; means associated with the 10 receiving end of said track for feeding a line of cans thereto; and a screw, the thread of which has an increasing lead engaging the cans of said in-feeding line to open the file for the timely association of its members 15 with said drain-covers.

20 6. A can-drainer comprising a sinuous can-inverting and reverting track; a traveling member following the sinuosity of said track; a series of spaced drain-covers carried by said traveling member adapted for fitting, propelling and releasing the respective members of a line of correspondingly spaced cans upon said track; means associated with the receiving end of said track for feeding a line 25 of cans thereto; a screw, the thread of which has an increasing lead engaging the cans of said in-feeding line to open the file for the timely association of its members with said drain-covers; and a fixed guide adapted in 30 conjunction with said screw to control the cans of said in-feeding line.

35 In testimony whereof I have signed my name to this specification.
